United States Patent

Des. 239,949
Patented May 18, 1976

239,949

GAME TARGET OR SIMILAR ARTICLE

Tito Trombetta, Jr., 40 Lawrence St.,
Danvers, Mass. 01923

Filed Apr. 16, 1973, Ser. No. 351,788

Term of patent 14 years

Int. Cl. D21—01

U.S. Cl. D34—5 PP

The figure is a perspective view of a game target or similar article showing my new design. The back is plain and unornamented and a similar support is present on the side not shown.

I claim:

The ornamental design for a game target or similar article, substantially as shown and described.
